United States Patent Office

Des. 212,043
Patented Aug. 20, 1968

212,043

THERMOMETER HOLDER

John R. Byrne, Watertown, Wis., assignor to Will Ross,
Inc., Milwaukee, Wis., a corporation of Wisconsin

Filed Nov. 15, 1967, Ser. No. 9,411

Term of patent 14 years

(Cl. D52—7)

Fig.1.

Fig.2.

Fig.3.

Fig. 4.

FIGURE 1 is a perspective view of a thermometer holder embodying my new design;

FIGURE 2 is a view from one side thereof; all sides being substantially the same in appearance as the side shown;

FIGURE 3 is a cross sectional view taken on the line 3—3 in FIGURE 2; and

FIGURE 4 is a perspective view showing a modification of the thermometer holder shown in FIGURE 1, the undisclosed portion being substantially the same in appearance as the portion shown.

I claim:

The ornamental design for a thermometer holder, as shown and described.
